UNITED STATES PATENT OFFICE.

JOHN W. RUSSEL, OF COLUMBIA, PENNSYLVANIA, ASSIGNOR OF ONE-HALF TO MARIETTA HOLLOW WARE AND ENAMELING COMPANY, OF MARIETTA, PENNSYLVANIA.

COMBINATION DRAIN BOARD AND COVER.

Application filed June 22, 1926. Serial No. 117,795.

This invention relates in general to an improvement in combination drainboards and covers for use with the combined type of kitchen sink and laundry tray, and more particularly the present invention is an improvement in the combination kitchen sink and laundry tray of the type forming the subject-matter of my co-pending application filed January 25, 1926, Serial Number 83,670.

One of the principal objects of the invention resides in the provision of a combination cover and drainboard of this character which seats down in the body of the combination sink and laundry tray structure so as to avoid the spilling of water and leaves the desirable clearance between the combined drainboard and cover and the spigots without the necessity of modifying the structure of the combination sink and laundry tray. Along with these advantages the present invention provides means which greatly facilitates the application and removal of the combined drain board and cover without danger of injuring the combination sink and tray construction. Accordingly the present invention provides a combination drainboard and cover having a body designed to completely cover the opening leading into the laundry tray. One end of the body of the combination drainboard and cover has a discharge section which extends over the partition of the combined sink and laundry tray. At the other end of the body of the combination drain board and cover an upwardly offset or curved hanger is provided and this curved hanger for the major portion of its extent covers the contour of the rounded upper edge of the outside wall of the combination tray and sink structure. Centrally of the offset hanger there is provided an upwardly disposed section which constitutes a handle below which a pocket is formed to receive the fingers or hand of the person applying or removing the combination drain board and tray. The hanger of the combination drain board and tray is stiffened by means of ribs or corrugations and at least two of the corrugations merge into the ends of the handle section to strengthen and stiffen the same.

Other objects and advantages reside in certain novel features of the construction, arrangement and combination of parts which will be hereinafter more fully described and

particularly pointed out in the appended claims, reference being had to accompanying drawings forming a part of this specification, and in which:

Figure 1 is a perspective view showing a combination sink and laundry tray equipped with a combined cover and drainboard embodying the present invention,

Figure 2 is a view thereof in central longitudinal vertical section, and

Figure 3 is an enlarged fragmentary perspective view showing the end of the combination cover and drainboard equipped with the hanger and handle.

Referring to the drawings the numeral 1 designates generally a combination sink and laundry tray structure which is of the usual type and has an outside wall 2, the upper edge of which is rounded and a partition 3, the upper edge of which terminates at 75 a level below the upper edge of the outside wall.

The present invention proposes the provision of a combined cover and drain board, designated generally at 5, and having a body 6 formed with a marginal flange and the usual drain channels. Preferably this body 6 is of such size and shape as to completely fill the opening leading down into the laundry tray or sink, as the case may be, it being understood that the combination drain board and cover is reversible; that is, adapted for use with either the tray or the sink of the fixture on which it is mounted. At one end the combination cover and drainboard 5 is provided with a discharge section 7 and at its opposite end has a hanger, designated generally at 8, constituted by a transversely reduced extension of the body of the tray. For the major portion of its transverse extent the hanger 8 is curved to snugly fit the rounded upper edge of the outside end wall 2 of the fixture and by virtue of the fact that this hanger is upwardly offset the drainboard is supported down in the tray or sink and below the upper edge of the outside wall, thereby preventing the spilling of water. This positioning of the combination drain board and cover down in the opening of the tray or sink makes it difficult to apply or remove the tray and when applying the tray it is sometimes dropped, thereby tending to injure the tray or the fixture. Applicant has remedied these disadvantages by providing the hanger with an upwardly dis-

posed or offset central section 9 which affords a handle or handgrip and which defines a pocket 10 to accommodate the fingers or hand of the operator. By inserting the fingers in the pocket 10 and grasping the upwardly displaced section 9 the drainboard may be conveniently manipulated. The metal of the hanger is stiffened and reinforced by ribs or corrugations 10, 11, 12 and 13 and the corrugations 11 and 12 merge into the portions of the section 9 of the hanger that connect with the main portion or section of the hanger, thereby strengthening the hanger section and stiffening the same at the points where it is liable to be weakened by the formation of the upwardly displaced central section 9.

One of the main features of the drain board resides in the fact that it is made of one piece metal without attachments and yet has the advantages and improvements pointed out hereinabove.

I claim:—

1. A combination drain board and cover for use with a combination laundry tray and sink comprising a one piece metal body having one end adapted to engage a partition of the combination laundry tray and sink and having an upwardly and outwardly curved extension defining a hanger at its opposite end designed to snugly engage the

rounded outside wall of the combination laundry tray and sink for the major portion of the extent of the hanger, the central portion of the hanger being struck-up providing a pocket between the hanger and the rounded upper edge of the outside wall of the combination laundry tray and sink permitting the fingers to be introduced under the hanger, the upwardly struck central section of the hanger constituting a hand grip, facilitating application and removal of the combination, cover and drain board.

2. The combination with a combined laundry tray and sink having an outside wall provided with an annular upper edge and also having a transverse partition, the upper edge of which partition is located below the plane of the upper edge of the outside wall, of a combined drain board and cover consisting of a one piece metal body fitting down in the opening of the tray or sink and completely covering the same, one end of said body having a discharge section engaging and overhanging the partition, the other end of said body having an upwardly and outwardly curved portion defining a hanger section adapted to snugly fit the rounded upper edge of the outside wall, said hanger section having a struck-up central portion providing a hand grip.

JOHN W. RUSSEL.
